Inventor:

Chas. E. Sweeney,
for W. D. Richards, Atty.

United States Patent Office.

CHARLES E. SWEENEY, OF GENESEO, ILLINOIS.

Letters Patent No. 90,406, dated May 25, 1869.

IMPROVED NECK-YOKE.

The Schedule referred to in these Letters Patent and making part of the same.

To all whom it may concern:

Be it known that I, CHARLES E. SWEENEY, of Geneseo, in the county of Henry, and State of Illinois, have invented certain new and useful Improvements in Neck-Yokes; and I do hereby declare that the following is a full, clear, and exact description of the construction and operation of the same, reference being had to the accompanying drawings, making a portion of this specification, in which—

Figure 1 is a longitudinal vertical sectional view of one end of a neck-yoke with my invention attached.

Figure 2 is a side view of the same.

Similar letters of reference indicate corresponding parts in all the figures.

The nature of this invention relates to improvements in neck-yokes for carriages, &c.; and

The invention consists in a simple arrangement of a hook, levers, and spring, whereby the hold-back breast-strap may be readily, easily, and quickly attached to the neck-yoke, and held firmly and securely against all danger of accidental release, at the same time admitting of being easily released when desired.

To enable others to understand the construction and operation of my invention, I will proceed to describe it with reference to the drawings.

Letter A represents one end of an ordinary neck-yoke for wagons, carriages, &c.

D represents a metal plate, seated in a suitable recess in the neck-yoke A, and secured by the screws E E.

J represents a lever, pivoted in a slot in the plate D, at j.

H represents a lever, pivoted, at h, in the same slot as J.

One side of the lever J lies flush to the outside of the neck-yoke A, and the other end lies on lever H.

P is a spring, attached at R to the plate D, and resting on the lever J.

L is a thumb-key, passing through the guard N.

C is the breast-strap, formed simply with a loop, for passing over the neck-yoke A.

The manner of operating my device is as follows:

Slipping the loop on the strap C over the end of the neck-yoke A to the position shown by c', it may readily be passed under the hook B, as it will throw down the projecting end of the lever H as it passes over it and when the strap reaches the position shown by C, the lever H will resume its position, and form a catch for holding the strap securely in position. Now, by pressing on the slide L, the lever H may be thrown in the position shown by the dotted lines, and the strap easily slipped from beneath the hook B.

It will also be seen, that while there is any strain (as in case of runaways, &c.) on the strap C, the lever J cannot assume the position shown by the dotted lines, and consequently cannot become released.

Having thus described my invention,

What I claim as new, and desire to secure by Letters Patent, is—

The combination of the lever J and spring P with the lever H, hook B, and plate D, and thumb-key L, substantially as described, and for the purpose set forth.

Signed at Galesburg, Illinois, this 11th day of March, 1869.

CHARLES E. SWEENEY.
